TOY VEHICLE

Samuel I. Berger, Newark, N. J.

Application November 29, 1933, Serial No. 700,173

6 Claims. (Cl. 46—48)

This invention relates to toys and more particularly to toy vehicles which are self-propelled by spring, electric, or other means.

Such self-propelled toys frequently collide with various objects so that the toy chassis is subjected to considerable stress and strain, especially at the front end.

It is an object of my invention to provide a means for reenforcing the chassis of a toy vehicle, and cooperating means for securing the front wheels of the toy in any one of several positions to thereby fix the course of travel of the toy.

A further object of my invention is to provide a toy vehicle having structural features designed to reduce the cost of manufacture to a minimum and to make the toy sufficiently simple in operation to enable it to be operated without any difficulty by children, and sufficiently rugged to withstand the rough treatment to which such toys are subjected.

A further object of my invention is to provide a carrier for batteries of toys, of novel and simple structure.

25 A further object of my invention is to provide a novel switch for toys having electric circuits.

A further object of my invention is to provide a novel arrangement for electrically connecting the light bulbs of a toy with a source of electric 30 circuit by the use of only one wire.

A further object of my invention is to provide various novel and efficient parts for the toy to simplify its construction and make it more efficient and durable in operation.

35 These and other advantageous objects which will later appear, are accomplished by the simple and practical construction and arrangement of parts hereinafter described and exhibited in the accompanying drawings, forming part hereof, 40 and in which:

Fig. 1 represents a bottom plan view of a toy automobile made in accordance with my invention.

Fig. 2 represents a fragmentary top plan view 45 of the chassis thereof, showing the switch in detail,

Fig. 3 represents a transverse vertical sectional view taken on lines 3—3 of Fig. 2,

Fig. 4 represents a perspective view of a tail 50 light plate and also a vertical sectional view thereof,

Fig. 5 represents a perspective view of the radiator and headlights of the toy automobile, parts being broken away for the sake of clarity,

55 Fig. 6 represents a transverse sectional view

of the chassis of the toy automobile taken through lines 6—6 of Fig. 1.

Fig. 7 represents a fragmentary perspective view of the member for supporting and electrically connecting the headlights,

Fig. 8 represents an exploded view of the parts used to reenforce the front end of the chassis and to fix the front wheels of the toy in either of three positions,

Fig. 9 represents detached perspective views 65 of the switch, and contact plates,

Fig. 10 represents a fragmentary perspective view of the chassis and battery carrier, parts being broken away for the sake of clarity, and

Fig. 11 represents a diagrammatic view showing 70 the preferred form of wiring and battery hook-up of my invention.

For the purpose of illustrating my invention, I have shown in the accompanying drawings, a toy automobile which is self-propelled by means 75 of batteries, but it will be apparent and it is intended that my invention is not limited thereto, but is equally well adapted for use in connection with other forms of toy vehicles, as will be apparent to any one versed in the art upon a 80 reading of the specification.

The automobile shown in the drawings, comprises a chassis 1 (see Figs. 1 and 2) preferably made from a single piece of suitable inexpensive metal, which is preferably provided with marginal channels 2 (see Figs. 6 and 10). A re-enforcing plate 3 (see Fig. 8) is secured to the underside of the chassis by any suitable means, preferably by providing the plate 3 with prongs 4 which are struck up therefrom, and are sheared 85 half way through the chassis 1, within aligned prongs 5 struck up from the chassis (see Fig. 2). The plate 3 is further provided with marginal channels 6 which are nestled within the marginal channels 2 of the chassis 1 as shown in 90 Fig. 6.

It has been found, in practice, that the re-enforcing plate thus described is efficient and effectively reenforces the front end of the chassis, which is, in the ordinary use of the toy most 100 frequently subjected to stresses and strains.

In the preferred form of my invention, one pair of wheels 8 of the device are secured to an axle 9 which passes through the channels 2 of the chassis 1 and is driven by motivating means 105 10 of the motor 11, while the other pair of wheels 12 are preferably carried by the bracket 13 (see Fig. 8) to which the head of a pin 14 is secured, the pin being provided with a portion 15 which freely passes through an aperture 16 in the plate 110

3 and an aligned aperture in the chassis and is then secured to the bowed spring 17 which bears upon the upper surface of the plate 3 (see Fig. 6).

The bracket 13 is provided with raised portions 18 which are designed to snap into any of the three pairs of apertures 7 in the plate 3, to position the wheels 12 in a plane either parallel with that of the chassis or at a left or right angle thereto. By this arrangement the wheels 12 may be positioned in either of three positions and it will be held against accidental displacement by the tension of the spring 17 as well as the registry of the raised portions 18 of the bracket 13 with the apertures 7 of the plate 3 (see Fig. 6). The plate 3 is further provided with fingers 19 over which tabs 20 of the radiator shell 21 may be clinched to hold the lower end of the radiator 21 in place, as shown in Fig. 1.

It will be obvious that the arrangement described may be used with equal efficacy in connection with any toy vehicle. However, in the form shown in the drawings, the arrangement is used in connection with a toy which is provided with a plurality of batteries 50 which are positioned on the underside of the chassis and are carried by the carrier plate 51 which is provided with marginal flanges 22, which overlap the flanges 25 of the chassis channel 2, as shown in Fig. 10. The plate 51 is further provided with transverse beads 23 which terminate just short of the flanges 22, at 24, thereby providing means for engaging both sides of the marginal flanges 25 of the channel 2. The carrier 51 is further provided with depressed portions 26 adapted to snap into recesses 27 in the flange 25 of the channel 2 as shown in Fig. 1, to normally hold the carrier in position to support all of the batteries.

A pair of ground contact plates 28, 28' are secured to an insulation sheet 29 by any suitable means such as by prongs 30, 30' integral with the plates 28, 28' and clinched over the sheet 29, the latter being secured to the chassis 1 by any suitable means as by chassis prongs 31.

The positive terminal of the battery 36 is electrically connected to the bulbs 37 by means of a wire 38 which at one end is secured to the contact 39 on insulation sheet 58' and at the other end is secured to plate 40 against which the positive terminals 41 of the bulbs 37 are adapted to bear when the bulbs are screwed into tubular socket members which are preferably integral with the bulb reflectors 45.

Strip 40 is preferably made of any suitable conducting material and is secured between the sheets of insulation 42 by any suitable means as by prongs 43 integral with the strip 40 and clinched over the sheet of insulation 42, the latter being carried in the channel member 44 which carries the bulb reflectors 45. The member 44 is positioned within recesses 46 in the side walls of the radiator shell 21 and is provided with prongs 47 aligned with the side walls of the radiator shell 21 and adapted to frictionally bear against the inside of the motor hood to make the structure more rigid.

The negative or ground terminal of the battery 36 as shown in Fig. 3, is frictionally engaged by the depending flange 48' of the contact plate 28'.

The batteries 50 are adapted to actuate the motor 11 and the positive terminal of the first of the batteries 50 engages the contact 39' on insulation sheet 58', the contact being connected to the motor 11 by means of the wire 52, while the

negative terminal of the last of the batteries 50, as shown in Fig. 11, is frictionally engaged by the depending flange 48 of the contact plate 28, a strip of insulation 53 being positioned between the depending flanges of the contact plates 28 and 28', as shown in Fig. 9. A spring member 57 is secured to an insulation sheet 58 on the underside of the chassis, and electrically connects the three batteries 50 as may be clearly seen in Fig. 11. In addition, the spring member 57 holds all of the batteries in contact position in the carrier plate 51. The rod 68 maintains the insulation sheets 58, 58' in spaced relation.

The ground contact switch shown in Fig. 9 is swivelly connected at one end to the chassis 1 by means of a rivet 33 (see Fig. 2) or the like passing through the sheet 29, the other end of the switch extending outwardly beyond the chassis 1. The switch is further provided with the spring finger 35 integral therewith and adapted to have sliding contact engagement with either of the plates 28, 28' or with both of the plates, in an intermediate position, or to be moved clear of the plates. Thus when the switch is in the position C, the spring finger 35 of the switch will contact with the contact plate 28' thereby providing a ground for the battery 36 and causing the bulbs 37 to light. It has been found in practice however, that when the toy is operated, the bulbs 37 may flicker upon the jarring of the toy which intermittently breaks the ground connection of the member 44. To prevent this, a flexible strip of metal 44' is secured, at one end, to the channel 44, the free end of the strip at all times frictionally engaging the radiator shell 21.

When the switch is in the position A shown in Fig. 2 the batteries 50 will be grounded as the switch contact finger 35 will then engage the contact plate 28 and when the switch is in the position B shown in Fig. 2 the switch contact finger 35 will bear upon the adjacent portions of both contact plates 28 and 28' so that the bulbs 37 will be lit and the motor 11 will be actuated. The position D in Fig. 2 is the off position of the switch.

If desired, the automobile chassis may be provided with a stop light 53 connected with the battery 36, or the toy may be provided with a combined license and tail light plate 54 preferably stamped from a single strip of material of the configuration shown in Fig. 4 and secured to the rear bumper 55 of the vehicle by any suitable means such as by a rivet or the like passing through the plate 54 and the bumper 55. The plate 54 is provided with an open boss 54' into which a metallic disc 55, which may be painted red, may be first positioned from the rear and then by forcing the material of the plates 54 over the disc 54' as shown at 56, in Fig. 4, the disc will be securely held within the plate.

The foregoing disclosure is to be regarded as descriptive and illustrative, and not as restrictive or limitative of the invention, of which obviously an embodiment may be constructed including modifications, without departing from the general scope herein indicated and denoted in the appended claims.

Having thus described my invention, what I claim as new and desire to secure by Letters Patent, is:

1. In a toy vehicle having a chassis provided with marginal channels, a reenforcing plate having complementary marginal channels nested within the marginally channelled chassis.

2. In a toy vehicle having a chassis provided with marginal channels, a reenforcing plate hav-

ing complementary marginal channels nestled within the marginally channelled chassis, and means for securing the plate to the chassis.

3. In a toy vehicle having a chassis provided with an aperture, a bracket carrying a pair of wheels, said bracket being provided with a pin passing through the aperture in the chassis and a bowed spring secured to the pin and bearing upon the chassis.

10 4. In a toy vehicle having a chassis provided with marginal channels, a reenforcing plate having complementary marginal channels nestled within the marginally channelled chassis, a bracket carrying a pair of wheels swivelly secured to the chassis, said bracket and reenforce-

ing plate having complementary means for securing the bracket in one of several positions relatively to the reenforcing plate.

5. In a toy vehicle, a plate provided with an open boss, and a disc of a color different from that of the plate, inserted into the open boss from one side thereof, the material of the plate being forced over the disc to secure the same within the boss.

80 6. In a toy vehicle, a plate provided with an open boss, and a disc inserted into the open boss from one side thereof, the material of the plate being forced over the disc to secure the same within the boss.
